METHOD OF AND APPARATUS FOR
POUNCING HATSPaul Schultze, Danbury, Conn., assignor to Doran
Brothers, Incorporated, Danbury, Conn.

Application May 29, 1941, Serial No. 395,885

24 Claims. (Cl. 223—20)

This invention relates to a method of and a machine for pouncing hat bodies.

One of the objects of this invention is to provide a machine for finishing hat bodies which is simple in construction, efficient in operation, and sturdy and durable under conditions of rigorous use. Another object is to provide a machine of the above nature which is substantially automatic in operation, and wherein the drive feed rate and control are effected hydraulically. Another object is to provide a machine of the above nature wherein the pouncing of the crown and brim of the hat may be completed in a single continuous operation without damage to any portion of the hat. Other objects will be in part apparent and in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the drawings, wherein I have shown one embodiment of my invention,

Figure 1 is an elevation of one side of my machine;

Figure 2 is a horizontal section taken along the line 2—2 of Figure 1;

Figure 3 is a fragmentary horizontal section, similar to Figure 2, but showing certain of the parts in a different operative position;

Figure 4 is a fragmentary horizontal section, similar to Figure 2, but showing the operating parts in still another operative position;

Figure 5 is an enlarged horizontal section taken along the line 5—5 of Figure 1;

Figure 6 is an enlarged fragmentary vertical section showing the manner in which the lower portion of the tool assembly is mounted on the base of the machine;

Figure 7 is an enlarged fragmentary front elevation showing a portion of the pouncing tool in operative engagement with the side of the hat and a portion of the brim thereof;

Figure 7A is an enlarged fragmentary side elevation showing a portion of the pouncing tool engaging a portion of the crown and brim of the hat; and,

Figure 8 is a diagrammatic elevation showing the hydraulic system.

Similar reference characters refer to similar parts throughout the several views of the drawings.

In general, and with reference to Figure 1, my

pouncing machine comprises a column generally indicated at 10 formed by a base section 11, a motor housing 12, and a head 13. A shaft is journaled in head 13 and has secured to one end thereof a chuck generally indicated at 14, which carries a hat block 15 on which a hat 16 may be mounted. On the other end of the shaft in head 13 is a driven pulley 17 connected by means of a belt 18 to a driving pulley 19 associated with a clutch generally indicated at 20. Clutch 20 is driven by a motor 21 mounted in housing 12 and thus shaft 13 may be driven to rotate hat block 15. Motor 21 also drives an oil pump 22 by means of pulleys 23 and 24 and belt 25, the oil pump preferably being mounted in the upper part of base 11 of column 10.

Rotatably mounted on a bracket generally indicated at 26 (Figure 1) secured to and extending from base section 11 is a pouncing tool assembly generally indicated at 27, which is movable about and toward and away from hat block 15 through mechanisms to be described hereinbelow. Pouncing tool assembly 27 includes a pouncing tool generally indicated at 200 and a driving mechanism therefor, as will also be described in detail hereinbelow.

Oil pump 22 (Figure 1) supplies oil under pressure to a hydraulic piston 28a (Figure 8) reciprocably disposed in a cylinder 28 (see also Figure 5) secured to the lower part of section 11 (Figure 1) of the machine column. As shown in Figure 5, a piston rod 29 extends through a gland 30 on cylinder 28 and has connected thereto a rack 31 supported by a guide 32 secured to bracket 26. Pouncing tool assembly 27 (Figure 6) is mounted on a heavy hollow post 33 which is rotatably journaled, as will be more particularly described hereinbelow, in a housing 34 or the like which may be an integral part of bracket 26 or connected thereto in any suitable manner. Preferably post 33 includes an annular shoulder 35 which has gear teeth cut therein which mesh with an idler gear 36 (Figure 5) in turn meshing with the teeth on rack 31. Thus, reciprocation of rack 31 causes rotation of post 33 (Figure 6) and accordingly rotation of pouncing tool assembly 27 about the axis of post 33. For a more detailed disclosure and description of these parts, reference is made to my United States Patent No. 2,105,130.

As shown in Figure 6, post 33 is carried by ball bearings 37 and 38 mounted respectively in the upper and lower ends of housing 34. The upper end of post 33 has integrally formed therewith a hollow arm 39 which extends at right angles

gles to the post. The outer end of arm 39 forms a housing 40 having a vertical axis and suitable upper and lower shoulders for the reception of ball bearings 41 and 42, respectively. These ball bearings 41 and 42 rotatably carry a hollow post 43, the bottom portion of which is provided with a plurality of ports 44 which permit communication between post 43 and hollow arm 39. The lower end of post 43 is sealed as by a plug 45. Formed integrally with and extending at right angles from the upper end of post 43 is a hollow arm 46, the free end of which forms a housing 47 carrying in its upper and lower portions ball bearings 48 and 49, respectively. These ball bearings rotatably mount a hollow post 50, the lower portion of which is provided with ports 51 which permit communication between this post and hollow arm 46. As in the case of post 43, the lower end of post 50 is sealed by a plug 52. It may now be seen that post 50 is rotatable relative to arm 46, which, in turn, is rotatable relative to post 33; post 50 accordingly also is rotatable relative not only to post 33, but also to bracket housing 34. Post 50 forms the bottom support of tool assembly 27, and it accordingly follows that the tool assembly is capable of free pivotal movement about the axis of post 50, as well as traversing movement about hat block 15 (Figure 1). It should also be noted that posts 33, 43 and 50, as well as hollow arms 39 and 46, are all in communication so as to provide in effect the lower end of an exhaust conduit, the purpose and operation of which will be described hereinafter. As shown in Figure 1, the lower end of this exhaust conduit connects with an elbow 53 which, in turn, is connected to an exhaust pipe 54, elbow 53 preferably being provided with a removable clean-out plate 55.

Pouncing tool assembly 27 (Figures 1 and 6) includes a lower housing 56 (Figure 6) within which an annular channel 57 is formed by an inner circular motor support 58. A pouncing tool operating motor 59 (Figure 1) is carried by support 58 (Figure 6) and has secured to one end of its armature (not shown) a pulley (not shown) which drives a belt 60 (Figure 1) which operates pouncing tool 200 as will be described. Tool assembly 27 also includes a tool housing generally indicated at 61, the lower portion of which is in the form of a hollow casting 62 (Figure 6) bolted or otherwise secured to the top of housing 56. Housing 62 accordingly communicates with conduit 57 in housing 56.

Tool housing 61 (Figure 1) is triangular in shape and is preferably integrally formed with lower casting 62. Three rollers 64, 65 and 66 are rotatably mounted in the upper, side and lower corners of housing 61 and have trained thereabout a sandpaper belt 67 which pounces hat 16 upon engagement therewith. The tension of belt 67 is adjustable through manipulation of adjusting mechanism generally indicated at 68 associated with upper roller 64. Lower roller 66 is mounted on an axle or spindle 69, the outer end of which carries a pulley (not shown) about which driving belt 60 is trained. Hence, upon operation of motor 59, roller 66 is driven to operate pouncing belt 67.

Tool housing 61 is provided with upper and lower open portions 70 and 71 to accommodate passage of belt 67 out of and into the housing. Lower opening 71 terminates at a point 72 so that material abraded from hat 16 may be drawn with the belt into housing 61, thence into cast-

ing 62, and thence into conduit 57 (Figure 6) from which the abraded material passes through the exhaust conduit formed by posts 50, 43 and 33.

As pointed out above, tool housing 61 is substantially triangular in shape and accordingly includes a base 73 and sides 74 and 75. The angle between sides 74 and 75 is preferably as large as possible so as not to reduce any more than necessary the contact between belt 67 and pulleys 64 and 66, as such reduction in contact between the belt and pulleys reduces the driving efficiency of pulley 66 and causes difficulties in maintaining the belt on the pulleys. The degree of the angle between housing sides 74 and 75 is, however, determined as to its maximum by the contour of the hat brim as the pouncing tool passes thereover (see Figure 7) as will be described more fully hereinbelow.

It will now appear that through the capacity of cylinder 28 (Figure 5) to drive rack 31, and by reason of the toggle joint formed, in effect, by arms 39 and 46 (Figure 6), and by reason of the driving mechanism for sandpaper belt 67 (Figure 1), the pouncing tool 200 is operable over the surface of hat 16. In general, this traversing operation of the pouncing tool is similar to that more particularly described in my United States Patent No. 2,137,250, to which, accordingly, reference is made for a more detailed description of the hydraulic and mechanical devices which not only effect the movement of the pouncing tool about the hat, but which also automatically control the feed rate of the tool about the hat. Hence, it will suffice to point out here that the pouncing tool is automatically advanced from what might be termed a loading station (see Figure 2), spaced from the hat block on one side thereof to a point adjacent the tip of the hat crown (see Figure 3) where the tool engages the hat. Thereafter the tool traverses the crown of the hat (see Figure 4) and returns to the point (Figure 3) at which it initially engaged the hat, from which point the tool is rapidly returned to the loading station (Figure 2), all of these operations being carried out automatically, as described in both of my aforesaid patents, and particularly Patent No. 2,137,250.

It should be noted that the axis of pouncing tool assembly 27 (Figures 1-4) is always vertical, regardless of the operative position of pouncing tool 200, by reason of the mounting of the tool assembly on the outer end of the toggle joint formed by arms 39 and 46. Accordingly, the travel of the tool assembly and tool is not limited to any prescribed path of movement, but is flexible in this respect so that hat bodies of varying and substantial depth can readily be operated on.

As the pouncing tool engages the hat during its traversing movement thereover, the pressure of the tool against the hat must be varied in accordance with the different positions of the tool on the hat as it passes thereover, in order that the finish given the hat be uniform. This variation in pressure is preferably timed in accordance with the variation in feed rate of the tool, as pointed out in my aforesaid patents, and in this connection I have found that where the pressure variations are effected by hydraulically controlled mechanism, superior results are obtained. To this end, and with reference to Figures 1-4, I have provided a cylinder 76 (Figure 1) within which a piston 76a (Figure 8) is reciprocable in accordance with the variation of oil pressure therewithin. This piston has a rod 77 (Figure 2)

attached thereto which extends from cylinder 76 through a packing gland 78, and has attached to one end thereof a flexible cable 79. This cable, as is more clearly shown in Figure 2, is trained around a pair of pulleys 80 and 81, rotatably mounted on suitable brackets secured to and extending from section 11 of machine column 10 and bracket 26, respectively. The other end of cable 79 is secured to a lug 82, extending from the outer end of arm 46 so that when the pouncing tool assembly 27 is in the positions shown in Figures 3 and 4, cable 79 is drawn toward and then around a third pulley 300 so that movement of piston rod 77 to the left, as viewed in these figures, pulls the pouncing tool assembly toward hat block 15, causing the pouncing tool to engage the hat with a definite, predetermined and variable pressure. It should be noted that pulley 300 is rotatably mounted on a stud 105 secured to and extending upwardly from the top of post 39.

The natural tendency of the pouncing tool is to move away from the hat, and accordingly the force exerted by cable 79 in pulling the tool against the hat is always resisted to a certain degree by the tool's tendency to move away from the hat, but as this tendency of the tool is only slight, the tool does not tend to bounce away from the hat during its travel thereover, as was often the case in prior machines of this character which relied on unbalanced spring and cam mechanisms for controlling and varying the pressure of the tool on the hat.

As hereinbefore noted, it is desirable that the pressure of the tool against the hat be varied as the tool traverses different portions of the hat. Accordingly I have provided a cam 83 (Figures 1-3) which, as is more clearly shown in Figure 6, is secured to the top of post 33 so as to rotate therewith. A cam follower 84 (Figure 3) is rotatably mounted on one end of a lever 85, extending from a hub 86 pivotally connected to a stud 87 mounted in a boss 88 (Figure 1) secured to section 11 of the machine column by a suitable bracket (not shown).

Referring back to Figure 2, a lever 89 is secured to the upper end of stud 87 so that movement imparted to lever 85 as follower 84 rolls over cam 83, is transmitted to lever 89. The free end of lever 89 is provided with a bifurcation 90 within which, as shown in Figure 1, is pivotally secured one end of a link 91. The other end of link 91 is adjustably secured to the slotted end 92 of a lever 93 pivotally mounted as at 94 on column 10 of the machine. It will now appear that movement of lever 89 is transmitted through link 91 to lever 93 so that the free end 95 thereof is moved up or down. Furthermore, this up or down movement of lever end 95 may be increased or decreased in accordance with the adjusted position of the left-hand end of lever 91 (as viewed in Figure 1) in the slot 92a in lever end 92.

Lever end 95 is operatively connected to the upper end of a valve plunger 96, which is reciprocably mounted within a conventional pressure regulating valve 97, the outlet chamber of which is connected to cylinder 76 by a pipe 98. If desired, pipe 98 may have connected thereto a pressure gauge 99. Valve 97 accordingly automatically controls the flow of oil into cylinder 76 and therefore controls the pressure exerted on the piston within this cylinder.

As is shown in Figure 8, oil pump 22 is connected by way of a pipe 100 to pressure regulat-

ing valve 97 which, as noted above, is connected to cylinder 76 by pipe 98. Oil flows out of cylinder 76 through a manually adjustable metering valve 101 into a pipe 102 which returns the oil to a reservoir in section 11 of machine column 10. It will now appear that as the oil pressure in cylinder 76 varies in accordance with the automatic adjustment of valve plunger 96 by movement of lever end 95, the piston 76a in cylinder 76 is moved in one direction or the other, and this movement is imparted to piston rod 77, and accordingly cable 79 (Figure 1) to vary the pressure of the pouncing tool against the hat. Thus, assuming that cam 83 is contoured in accordance with the desired pressures, the pressure of the pouncing tool against the hat at any portion during its traversing movement thereover may be of a predetermined, desired value. It might be noted that cylinder 76 (Figure 1) is preferably provided with a vent 103 communicating with that portion of the cylinder to the right of piston 76a, as viewed in Figure 8, so that there will be no restriction on the movement of the piston.

As shown in Figure 2, pouncing tool assembly 27 is at the loading station, i. e., the assembly is well spaced to one side of the hat block 15, whereas in Figure 3, the pouncing tool assembly is shown in the position wherein the pouncing tool first engages or leaves the tip of the hat. Figure 4 shows the pouncing tool assembly 27 at the end of its forward travel. As the pouncing tool assembly travels from the position shown in Figure 3 to the position shown in Figure 4, and back again, the hydraulic control previously described maintains the pouncing tool against the hat at predetermined pressures. However, on the return stroke of the pouncing tool assembly, it must be moved from the position shown in Figure 3 to that shown in Figure 2, and to that end I provide the mechanism now to be described.

As shown in Figure 2, arm 46 has bolted thereto a gear sector 104, which accordingly moves with the arm. As noted above, the main swinging arm 39 carries stud 105 on which a gear sector 106 is loosely mounted, this latter sector meshing with gear sector 104. Gear sector 106 includes a hub 107, to which is bolted a bar 108, the free end of which swings toward and away from a post 109, which is secured to and extends upwardly from bracket 26 (see Figure 1). On the upper end of this post is adjustably mounted an eccentric head 110 which may be secured in any desired position by means of a nut 111 threaded on the reduced end 112 of stud 109. When the pouncing tool assembly 27 is in pouncing position at the tip or the side crown of the hat, as shown in Figures 3 and 4, the gear sectors 104 and 106 do not interfere with the free movement of arms 39 and 46 relative to each other, as gear sector 106 is loosely mounted, as described. However, as the pouncing tool assembly 27 during its return travel from its position shown in Figure 4, moves to the position shown in Figure 3, bar 108 on loose gear sector 106 gradually approaches eccentric head 110. When bar 108 engages head 110 during this counterclockwise movement of main swinging arm 39, as viewed in Figure 3, further movement of gear sector 106 is impossible. Hence, further counterclockwise movement of main swinging arm 39 causes gear sector 104 and arm 46 to rotate about their axes, i. e., the pivotal axis of arm 46. This rotative movement of gear sector 104 and arm 46 causes pouncing tool assembly 27 to move away from the hat body to the position shown in Figure 2. It

might be added that this return movement to what has been termed the loading station is effected at a rapid rate through an automatic control of the hydraulic driving system, as described in my aforesaid patents. By reason of the adjustability of eccentric head 110, the position of contact of bar 108 with head 110 can be varied at will so that the point of contact of the pouncing tool with the hat and the point of removal of the tool from the tip of the hat may be varied.

It will now appear that the movement of pouncing tool assembly 27, and accordingly the pouncing tool, toward and away from hat crown 15 is under positive automatic control which, together with the automatic pressure control afforded through the mechanism incorporating hydraulic cylinder 76, assures a uniform finish on the hat being pounced. It should also be noted that through the provision of swinging arms 39 and 46, the axis of pouncing tool assembly 27 is always vertical, regardless of the movement of the tool assembly toward and away from or about hat block 15.

As pointed out in my copending application, Serial No. 226,442, filed August 24, 1938, it is desirable that the pouncing of the crown of the hat and the brim thereof be carried out in one continuous operation so as to obviate the use of separate machines for crown and brim pouncing, and the consequent loss of time in transferring the hat from one machine to another. Furthermore, the continuous pouncing operation imparts a uniform finish to both the crown and brim of the hat, as the conditions under which each is pounced are identical. One aspect of my invention described herein is accordingly directed to an improvement of the mechanism disclosed and described in my aforesaid copending application. This improved mechanism will now be described.

As shown in Figures 1 and 2, main swinging arm 39 has secured thereto a cam 113, which rotates with the arm. The surface of this cam engages a follower 114 carried on one end 115 (Figure 1) of a bell crank generally indicated at 116, which is pivoted to the upper end of a bracket 117, the lower end of which is suitably secured to bracket 26. The other end 118 of bell crank 116 is pivotally connected to the lower end of an elongated rod 119, which extends vertically along the side of column 10 and passes through a guide and support bracket 120 secured to and extending from the upper end of column 10. The upper end of rod 119 (see Figure 7) engages the under side of an arm 121, the right-hand end of which is secured to a hub 122, pivotally mounted on a shaft 123 (see also Figure 1), which is supported by a pair of brackets 124 secured to and extending upwardly from head 13. On the outer or right-hand end of shaft 123, as viewed in Figure 7A, is coiled a spring 124, one end of this spring being secured to the shaft, and the other end being secured to hub 122 so that arm 121 (Figure 7) is given a counterclockwise bias.

Still referring to Figure 7, arm 121 has secured thereto a brim depressor 125 which, when in the full line position, engages brim 16a of hat 16 and flattens out the brim in the vicinity of the path of travel of pouncing tool 200 so that as sandpaper belt 67 is pressed against the hat by roller 65, the hat brim is flattened and is accordingly not rumpled or creased or cut from the pressure of the pouncing tool thereagainst. As hereinbefore noted, the angle between sides

74 and 75 of pouncing tool housing 61 should be as large as possible, and the degree of this angle is accordingly determined by the angle (which should be as large as possible) between portions 16b and 16c of hat brim 16a when the hat brim is depressed by depressor 125.

It is desirable that brim depressor 125 be in its brim depressing or solid line position, as shown in Figure 7, for as short a time as possible, so as to avoid unduly "mellowing" the hat brim, and to this end cam 113 (Figure 2) is contoured. In this connection, it might be noted that hat brims are often treated with a stiffening substance, such as shellac, for example, and if the brim is manipulated excessively during the pouncing operation the brim is softened or "mellowed." Thus, when the pouncing tool approaches the point indicated at A on hat 16 (Figure 1) high point 113a (Figure 2) of cam 113, is adjacent follower 114. As high point 113a passes the follower, the contour of cam 113 rapidly drops to its smallest diameter 113b, with the result that counterclockwise movement of bell crank 116 occurs by reason of downward movement of rod 119 under the bias of spring 124 operating through arm 121. This downward movement of rod 119 permits brim depressor 125 to move to its brim depressing position, shown in Figure 7, in which position the depressor remains during the forward and reverse travel of the pouncing tool over that portion of the hat crown adjacent the brim and the brim portion. When the pouncing tool, on its return travel, reaches the point A on hat 16 (Figure 1) high spot 113a (Figure 2) of cam 113 bears against follower 114, resulting in clockwise movement of bell crank 116 (Figure 1) and upward movement of rod 119. Upward movement of rod 119 swings arm 121 and accordingly depressor 125 clockwise, as viewed in Figure 7, thus removing the depressor from the hat brim to the dotted line position.

It will now appear that as the pouncing tool traverses the hat, it reaches a point adjacent the brim of the hat at which depressor 125 is automatically caused to depress the brim, thus enabling continued traversal of the pouncing tool over the brim and back again without rumpling, creasing or otherwise damaging the brim. Accordingly, the finish imparted to the brim is the same as that imparted to the crown, and this without damage to either.

Motor 59 (Figure 1) drives sandpaper belt 67 in such a manner that the belt is moving in the same direction as the hat block during the engagement of the belt with the side crown and the brim of the hat. The belt, however, has a substantially greater velocity than the hat block or hat, and this differential in velocity is utilized during the travel of the pouncing tool over the brim to impart a feed or movement of the brim relative to the hat block by reason of the brim's greater diameters. Thus the more rapidly moving belt 67 as it travels over the brim, pulls the brim along with it, in effect causing the brim to move faster than the adjacent surface of the hat block so that the brim is not rumpled, creased or cut as it is pounced.

It should also be noted that as the pouncing belt 67 moves from the side crown of the hat onto the brim, it simultaneously pounces a portion of the side crown and a portion of the brim, thus imparting a finish to the angle between the brim and side crown of the hat, a portion of the hat heretofore difficult or impossible to pounce

subsequent to blocking, or at least partial blocking of the hat. Thus, it will appear that pouncing tool 200 has two functions, the first of which is to impart a feed rate to the brim so as to maintain the brim flat against the hat block as the pouncing tool passes over the brim, and second to pounce the crown and brim of the hat in one continuous operation so that each has imparted thereto the same finish as the other.

Inasmuch as operation of sandpaper belt 67 (Figure 1) is unnecessary when the belt is out of engagement with the hat during the movement of the pouncing tool assembly 27 between the positions shown in Figures 2 and 3, I have provided mechanism for automatically deenergizing motor 59 which drives sandpaper belt 67. It is equally unnecessary to continue rotation of hat block 15 during this period of travel of the pouncing tool assembly, and this mechanism is also directed to stopping operation of the hat block.

In the circuit of motor 59 (Figure 1) is a switch 126, operation of which energizes or deenergizes the motor circuit. Switch 126 has an operating arm 127 extending therefrom, and this arm is connected in any suitable manner to a rod 128 reciprocably mounted on the side of column 10. The lower end of rod 128 is slidably connected to another rod 128a which, in turn, is connected to one arm of a bell crank lever 129, the other arm of which is connected to one end of a rod 130 (Figure 5), see also my Patent No. 2,137,250. The other end of rod 130 is pivotally connected to one end of a lever 131 pivotally mounted as at 132 on bracket 26. The other end 131a, of lever 131, pivotally supports an arm 133, one end 133a of which is connected by a spring 134 to a post 135 secured to and extending from bracket 26. The other end 133b of arm 133 has a slot 136 formed therein adapted to receive a stud 137 secured to and extending from a plate 138 connected to idler 36, and accordingly rotatable therewith. Plate 36 also has extending therefrom another stud 139, the purpose of which will be described hereinbelow.

Idler gear 36 moves clockwise, as viewed in Figure 5, during the return traverse of the pouncing tool assembly 27 (Figure 4) and when the tool assembly is in the position shown in Figure 3, just prior to its movement away from hat crown 15, stud 137 (Figure 5) enters slot 136 so that continued clockwise movement of idler 36 pulls arm 133 to the right to cause clockwise movement of lever 131. This movement of the lever is transmitted by way of rod 130, bell crank 129, and rod 128a to rod 128 (Figure 1) causing rod 128 to move upwardly and move switch arm 127 to its open position, breaking the circuit to motor 59 and accordingly stopping movement of sandpaper belt 67.

Rod 128 is also connected by a system of levers and rods to clutch 20 as particularly described in my Patent 2,137,250, so that upward movement of rod 128 also causes clutch 20 to disengage and accordingly cease to drive hat block 15. Thus operation of both the sandpaper belt and the hat crown are automatically stopped when the pouncing tool is removed from the hat.

Referring back to Figure 5, it will be noted that spring 134 biases arm end 133b against studs 137 and 138, so as to assure entrance of stud 137 into slot 136. To preclude jamming the linkage comprising arm 133, lever 131, rod 130 and rod 128 (rod 128 having a relatively short travel) and also to permit the linkage to return to its starting position, it is desirable to disengage

arm 133 from stud 137 after switch 126 (Figure 1) has been opened. It is to accomplish this that stud 139 (Figure 5) is provided. During the clockwise movement of idler 36, stud 139 also 5 swings clockwise until it engages arm 133 to the left of slot 136. Continued clockwise movement of the idler and stud 139 accordingly forces arm 133 counterclockwise against the bias of spring 134, forcing the arm away from slot 137 so that 10 continued clockwise movement of stud 131 will not jam the linkage system to rod 128, and will permit its return to its starting position.

It may now be seen that I have provided a pouncing machine which attains in a thoroughly 15 practical and efficient manner the several objects set forth hereinabove.

As many possible embodiments may be made of the mechanical features of the above invention and as the art herein described might be varied 20 in various parts, all without departing from the scope of the invention, it is to be understood that all matter hereinabove set forth, or shown in the accompanying drawings is to be interpreted as illustrative and not in a limiting sense.

I claim:

25 1. A machine of the character described, in combination, a base, a hat support rotatably mounted on said base, a tool support, a tool operatively mounted on said tool support, means operatively connecting said tool support and said base for relative movement therebetween along a path extending substantially from the tip of a hat mounted on the hat support to the outer edge of the brim of the hat, a brim depressor pivotally associated with one of said supports, means for maintaining said depressor in a normally inoperative position spaced from the hat, and means for pivoting said brim depressor from said inoperative position into operative engagement with said hat brim as said tool passes thereover.

30 2. A machine of the character described, in combination, a base, a hat support rotatably mounted on said base, a tool support, a tool operatively mounted on said tool support, means operatively connecting said tool support and said base for relative movement therebetween along a path extending substantially from the tip of a hat mounted on the hat support to the outer edge of the brim of the hat, a brim depressor pivotally associated with one of said supports and movable into and out of engagement with said hat, means for maintaining said depressor in a normally inoperative position spaced from the hat, and means for biasing said depressor from said inoperative position into its brim engaging position as said tool passes over the brim.

35 3. A machine of the character described, in combination, a base, a hat support rotatably mounted on said base, a tool support, a tool operatively connecting said tool support and said base for relative movement therebetween along a path extending substantially from the tip of a hat mounted on the hat support to the outer edge of the brim of the hat, a brim depressor pivotally associated with one of said supports and movable into and out of engagement with said brim, means for maintaining said depressor in a normally inoperative position spaced from the hat, means for biasing said depressor from said inoperative position into its brim engaging position as said tool passes over the brim, and means for moving said brim depressor out of engagement with said brim subsequent to the operation 40 of said tool on said brim.

4. A machine of the character described, in combination, a base, a hat support rotatably mounted on said base, a tool support, a tool operatively mounted on said tool support, means for pivotally connecting said tool support to said base to permit relative movement between said tool and said hat support along a path extending substantially from the tip of a hat mounted on said hat support to the outer edge of the brim of the hat, means for effecting said relative movement, a brim depressor pivotally associated with one of said supports and movable into and out of engagement with said brim, means for maintaining said depressor in a normally inoperative position spaced from the hat, and means including a cam associated with one of said supports for effecting movement of said depressor from said inoperative position to its brim depressing position as said tool passes over the brim.

5. A machine of the character described, in combination, a base, a hat support rotatably mounted on said base, a tool support, a tool operatively mounted on said tool support, means for pivotally connecting said tool support to said base to permit relative movement between said tool and said hat support along a path extending substantially from the tip of a hat mounted on said hat support to the outer edge of the brim of the hat, means for effecting said relative movement, a brim depressor pivotally associated with one of said supports and movable from a normally inoperative position spaced from the hat into and out of engagement with said brim, a cam connected to said tool support, and follower mechanism operatively associated with said cam and said depressor for effecting movement of said depressor between its brim engaging and disengaging positions in accordance with the position of said tool with respect to said brim.

6. A machine of the character described, in combination, a base, a hat support rotatably mounted on said base, a tool support, a tool operatively mounted on said tool support, means for pivotally connecting said tool support to said base to permit relative movement between said tool and said hat support along a path extending substantially from the tip of a hat mounted on said hat support to the outer edge of the brim of the hat, means for effecting said relative movement, a brim depressor pivotally associated with one of said supports and movable into and out of engagement with said brim, a cam associated with said tool support, and a follower mechanism operatively connecting said cam and said depressor for effecting movement of said depressor into its brim engaging position immediately prior to the engagement of said tool with that portion of the hat underlying said depressor.

7. A machine of the character described, in combination, a base, a hat support rotatably mounted on said base and adapted to support a blocked hat, a pouncing tool operatively associated with said base and movable relative thereto along a path extending substantially from the tip of said hat to the outer edge of the brim thereof, a member pivotally associated with said hat support adjacent the brim of said hat and normally out of engagement therewith, and means for pivoting said member into engagement with said hat to depress said brim only during the engagement of said tool with said brim and a portion of the crown of the hat.

8. A machine of the character described, in combination, a column comprising a base and a head secured thereto, a hat support rotatably

mounted on said head, a tool support pivotally connected to said base, a tool mounted on said tool support, means on said column for effecting relative movement between said tool and said hat support along a path extending substantially from the tip of a hat, a shaft mounted on said head, a plate-like brim depressor member pivotally mounted on said shaft, and spring means associated with said shaft and said depressor member for forcing said depressor member against the brim of a hat mounted on said hat support to force said brim against said hat support in a position to be engaged by said tool.

9. A machine of the character described, in combination, a column comprising a base and a head secured thereto, a hat support rotatably mounted on said head, a tool support pivotally connected to said base, a tool mounted on said tool support, means on said column for effecting relative movement between said tool and said hat support along a path extending substantially from the tip of a hat, a shaft mounted on said head, a plate-like brim depressor member pivotally mounted on said shaft, spring means associated with said shaft and said depressor member for forcing said depressor member against the brim of a hat mounted on said hat support to force said brim against said hat support in a position to be engaged by said tool, and means for forcing said depressor member out of engagement with said brim.

10. A machine of the character described, in combination, a rotatable hat support adapted to support and rotate a blocked hat, means for rotating said support, means for pouncing the surface of said hat, said pouncing means including a sandpaper belt, means for depressing the brim of said hat during the operation of said sandpaper belt thereon, and driving means for operating said belt at a surface speed substantially in excess of the surface speed of said hat and in the same direction, whereby when said belt engages said brim the brim is moved relative to said hat support and in the same direction.

11. A machine of the character described, in combination, a rotatable hat support adapted to rotate and support a blocked hat, means for rotating said support, means for pouncing the surface of said hat, means for depressing at least a portion of said hat during the operation of said pouncing means thereon, said pouncing means including a triangular shaped housing and a sandpaper belt revolvably mounted therein, and means for driving said belt at a surface speed in excess of the surface speed of said hat support so as to move said hat brim relative to said hat support but in the same direction during its engagement therewith.

12. A machine of the character described, in combination, a rotatable hat support adapted to support and rotate a hat, a pouncing tool, means mounting said pouncing tool for movement relative to said hat along a path extending substantially from the tip of the hat toward the brim thereof, a hydraulic device including a reciprocable piston, means forming a connection between said piston and said pouncing tool for forcing said tool against said hat upon movement of said piston in one direction, and means responsive to the relative movement between said tool and said hat for controlling the movement of said piston to vary the pressure between said tool and said hat.

13. A machine of the character described, in combination, a rotatable hat support adapted to

support and rotate a hat, a pouncing tool, means mounting said pouncing tool for movement relative to said hat along a path extending substantially from the tip of the hat toward the brim thereof, a hydraulic device including a reciprocable piston, a hydraulic device including a cylinder and piston and a regulating valve for varying the fluid pressure in said cylinder, means connected to said piston and to said tool for transmitting the pressure exerted by said hydraulic device to said tool to force said tool against said hat, and means operatively associated with said tool and said valve and responsive to movement of said tool for varying the pressure within said cylinder thereby to vary the pressure of said tool against said hat.

14. A machine of the character described, in combination, a base, a hat support rotatably mounted on said base and adapted to support and rotate a hat, means for rotating said hat support, an arm pivotally secured to said base and pivotable about a stationary vertical axis, a second arm pivotally connected to said first arm and pivotable about a vertical axis, a pouncing tool pivotally mounted on said second arm and pivotable about a vertical axis, all of said axes being at all times parallel, means for traversing said tool over the surface of said hat, means for forcing said tool against said hat during its traversing movement, and means associated with said arms and operable upon relative movement therebetween for effecting movement of said tool away from said hat subsequent to its traversing movement thereover.

15. A machine of the character described, in combination, a base, a hat support rotatably mounted on said base and adapted to support and rotate a hat, means for rotating said hat support, means forming a toggle joint, means for pivotally connecting one end of said toggle joint to said base, a pouncing tool pivotally mounted on the other end of said toggle joint, means for traversing said tool over the surface of said hat, means for forcing said tool against said hat during its traversing movement thereover, said last-mentioned means including a hydraulic mechanism, and means for varying the pressure in said hydraulic mechanism for varying the force with which the tool bears against the hat during its traversal thereover.

16. A machine of the character described, in combination, a base, a hat support rotatably mounted on said base and adapted to support and rotate a hat, means for rotating said hat support, means forming a toggle joint, means for pivotally connecting one end of said toggle joint to said base, a pouncing tool pivotally mounted on the other end of said toggle joint, means for traversing said tool over the surface of said hat along a path substantially from the tip thereof toward the brim, and gear means associated with said toggle joint for effecting movement of said tool away from said hat subsequent to its traversal thereover.

17. The herein described art which includes the steps of rotating a partially blocked hat, engaging said hat with a pouncing tool, moving said tool over the surface of said rotating hat along a path starting at the tip of the hat and extending therefrom toward the brim of the hat, depressing the brim of the hat as the tool moves over the side crown portion of the hat, continuing the movement of the tool over the brim of the hat to the outer edge thereof, and moving

the brim of the hat during its engagement with the tool at a greater rate than the rate of movement of the side crown of the hat.

18. A pouncing machine for pouncing a partially blocked hat, in combination, a base, a hat support rotatably mounted on said base, said hat support comprising a hat block rounded to fit the inside of a hat on which a partially blocked hat is adapted to be mounted and held thereon by frictional engagement therewith so that the crown of the hat is firmly supported by the block and the brim of the hat extends outwardly of and is entirely unsupported by the block, a tool support, a tool operatively mounted on said tool support, means operatively connecting said tool support and said base for relative movement therebetween along a path extending substantially from the tip of a hat mounted on said hat support to the outer edge of the brim of the hat, and means for depressing the hat brim as the tool passes thereover so as to force the outwardly extending brim to a position on or adjacent to the surface of the hat block to facilitate movement of the tool over the flattened portion of the brim.

19. A machine of the character described, in combination, a base, a hat support rotatably mounted on said base, a tool support, a tool on said tool support, means operatively connecting said tool support and said base for relative movement therebetween along a path extending substantially from the tip of a hat mounted on said hat support to the outer edge of the brim of the hat, and means for engaging the hat brim and forcing it against said hat support as the tool passes thereover, said brim engaging means and said tool being immediately adjacent one another during the passage of the tool over the brim.

20. The herein described art which includes the steps of, mounting a partially blocked hat on a rotating hat block with the brim extending outwardly therefrom and unsupported thereby, engaging said hat with a pouncing tool, moving said tool over the surface of said hat along a path extending between the tip of the hat and the brim edge thereof, and flattening that portion only of the brim of the hat engaged by the tool as the tool moves thereover.

21. The herein described art which includes the steps of, mounting a partially blocked hat on a rotating hat block with the brim extending outwardly therefrom and entirely unsupported thereby, engaging said hat with a pouncing tool, moving said tool over the surface of said hat along a path extending between the tip of the hat and the brim edge thereof, forcing the brim of the hat against the block during the movement of the tool over the side crown portion of the hat, and continuing the movement of the tool over the brim of the hat to the outer edge thereof while maintaining the brim in engagement with the block.

22. A machine of the character described, in combination, a rotatable hat support adapted to support and rotate a hat having a brim extending from the crown thereof, means for rotating said support, means for pouncing the surface of said hat and for imparting a feed rate to said brim in excess of its normal rate of movement during the pouncing operation, and means for depressing the brim of said hat to engage it with said hat support during the pouncing operation.

23. A machine of the character described, in combination, a rotatable hat support adapted to support and rotate a hat, a tool support, a pouncing tool on said support, means mounting said

pouncing tool for movement relative to said hat along a path extending from the tip of the hat toward the brim thereof, a hydraulic device operable for forcing said pouncing tool against said hat during its travel thereover, a valve operable to admit fluid under pressure into said hydraulic device to effect operation thereof and means associated with said tool support and responsive to the position thereof for effecting operation of said valve.

24. A machine of the character described, in combination, a rotatable hat support adapted to support and rotate a hat, a pouncing tool, means

mounting said pouncing tool for movement relative to said hat along a path extending substantially from the tip of the hat toward the brim thereof, a hydraulic device including a reciprocable piston, means forming a connection between said piston and said pouncing tool for forcing said tool against said hat upon movement of said piston in one direction, a valve for controlling the fluid flow to said hydraulic device, and means including a cam associated with said pouncing tool for operating said valve.

PAUL SCHULTZE.
